UNITED STATES PATENT OFFICE.

HERNÁN C. BELLIDO, OF HABANA, CUBA, ASSIGNOR TO ALFREDO DE LA FUENTE Y QUIÑONES, OF HABANA, CUBA.

WRAPPING MACHINE.

Application filed April 9, 1921. Serial No. 460,038.

To all whom it may concern:

Be it known that I, HERNÁN C. BELLIDO, a citizen of the Republic of Peru, and resident of Habana, Cuba, whose postal address is No. 437 Lonja Building, Habana, Cuba, have invented certain new and useful Improvements in Wrapping Machines, of which the following is a specification.

This invention relates to wrapping machines, particularly to the machines designed for wrapping cigarettes and its main object is to provide a machine which is capable of making packages or wrappers for cigarettes of different sizes and the operating parts of which are made adjustable.

A further object of the invention is to provide means whereby certain portions of the cigarette pushing plunger can be made inoperative at will during the operation of the machine.

A further object of the invention is to provide means whereby the actuating members of the cigarette package compressing device are simplified.

A further object of the invention is to provide means whereby the front of the cigarette package pushed by the plunger is caused to fall in a perfectly vertical plane and at the same time centralize the same so that the same projecting portions may appear at each side of the cigarette package.

Another object of the invention is to provide an improvement in the folding means of the blank.

Still a further object is the provision of a blank feeding device capable of being continually operated, which is automatically actuated by vacuum and which operates simultaneously with the various parts thereof.

And still a further object of the invention is the provision of a device for drying the wrapper when being finished by the machine.

Further objects and advantages of the invention will be readily understood in the course of this specification, reference being had to the annexed drawings in which the same reference characters indicate the same parts throughout the various figures.

In the annexed drawings:

Fig. 1 is an upper plan view of the machine.

Fig. 2 is a side elevation thereof,

Fig. 3 is a front elevation of the machine.

Fig. 4 is an elevation of the rear part of the machine.

Fig. 5 is a horizontal section of the machine on line 5—5 of Fig. 2.

Fig. 6 is a longitudinal vertical section on line 6—6 of Fig. 1.

Fig. 7 is an enlarged partial vertical section on line 7—7 of Fig. 8.

Fig. 8 is an enlarged partial horizontal section on line 8—8 of Fig. 7.

Fig. 9 is a detailed cross vertical section of the magazine or feeder of cigarettes on line 9—9 of Fig. 8.

Fig. 10 is a detail cross vertical section of the cigarette compressing device on line 10—10 of Fig. 8, showing the operating mechanism thereof.

Fig. 11 is a detail cross vertical section of said device showing the end of the operation thereof.

Fig. 12 is a detail upper plan view of the blank feeder or device for feeding the blanks.

Fig. 13 is a detail longitudinal vertical section on line 13—13 of Fig. 12.

Fig. 14 is a detail longitudinal vertical section showing an operative position of the suctioning device when pulling a blank out of the deposit.

Fig. 15 is a detail cross vertical section on line 15—15 of Fig. 8.

Fig. 16 is a detail cross vertical section on line 16—16 of Fig. 8.

Fig. 17 is a detail cross vertical section on line 17—17 of Fig. 8.

Fig. 18 is a detail cross vertical section on line 18—18 of Fig. 8.

Figs. 19 and 20 are longitudinal vertical sections of two different positions of the folding device.

Figs. 21, 22, 23, 24, 25, 26, and 27 are perspective views showing the successive phases of the folding of the blank to constitute a package or rectangular wrapper of cigarettes.

In the drawing 1 indicates a frame supported on four supports 2 and on which is arranged a platform or working table 3 beneath which are revolubly mounted two parallel shafts 4 and 5 provided at one end with gear wheels 7 and 6, which mesh with a pinion 8 mounted on a short driving shaft

9 having a loose pulley 10 and a fixed one 11 which receive motion from a convenient power source which is not shown.

Between supports 2 are fixed cross bars 5 12 and 13 connected together by means of a bar 14, about the middle part of which is pivoted a lever 15 which is connected by means of a connecting-rod 16 to a crank 17 on a cross shaft 18 revolvable on a supporting 10 frame 19 fixed beneath the table 3 and provided inside of said frame with a bevel pinion 20 which meshes with a similar pinion 21 fixed on shaft 4.

Lever 15 is connected at its upper end by 15 means of a link 22 to a sliding block 23 formed by the rear part of a plunger or cigarette pusher and which block reciprocates on a horizontal guide 24 on table 3. At the center of said block is fixed by means 20 of screws a cigarette plunger or pusher 25 longitudinally slotted at its center with the object that will be hereinafter explained, and at the sides thereof are removable boards 26 and 27 which are fixed to block 23, one 25 above and the other one below the same by means of screws having wing nuts 28 which permit said boards to be arranged at will at right angles with respect to the plunger 25 as indicated by slotted lines in Fig. 1.

30 On shaft 5 are mounted a cam 29 which operates the cigarette compressing mechanism, a cam 35 which operates the blank centralizer, a cam 31' which operates the blank feeder, a cam 31 which operates one 35 of the head folders and a cam 32 which operates a movable roller of the paster.

On shaft 4 are mounted a cam 30' which 40 operates the vacuum cut off valve, a cam 35 which operates the actuating mechanism of the cigarette magazine, a cam 34 which operates the compressing mechanism, a cam 30 which operates the blank centralizer, a bevel pinion 36 which operates the paster, a cam 37 which operates the opposite head folder 45 and a cam 38 which operates the movable part of the folder.

The magazine or feeder of cigarettes illustrated in Fig. 9 comprises a casing 39 above the bottom of which at opposite sides are 50 arranged two groups of vertical partitions 40 and 41 separated by a chamber 42 which is closed at the upper part and at the side and opened at its ends, said partitions terminating at a short distance from the bottom 55 of the casing to form spaces 43 and 44 arranged on different horizontal planes through which the boards 26 and 27 fixed to the sliding block 24 can pass. Said plunger 25 being arranged to pass through 60 the chamber 42. The magazine is provided with perforated inclined double walls 45 at opposite sides fixed to a horizontal frame 46 which is arranged for reciprocating movement by a lever 47 which lever is operated 65 by the cam 35 of shaft 4. Said lever is

mounted on a support 49 and moves in an opening 48 as shown.

The compressor is formed by two superposed casings 50 and 51 arranged on the table 3 behind the recorder and in such a 70 manner that in its central position it may be separated only by the horizontal partition 52 which extends into the chamber 42, said partition permitting the passage of the plunger by being arranged in the slot thereof as shown in Fig. 7 when said plunger is in one position.

Said casings have a cover 53 which is hinged at 54 and provided at its front edge with wing nut screws 55 which permit said 80 cover to be raised. Said cover has glazed observation openings 56 and 57.

Plungers 58, 59 operate in opposite sides of said casing, and are respectively actuated by levers 60 and 61 which are operated, 85 one by cam 29 of shaft 5 and the other by the cam 34 of shaft 4. Said levers are respectively mounted on supports 64, 65 and move in openings 62, 63.

A conduit 66 of oblong rectangular form 90 in vertical cross section, leads from the central portion of the compressor casing 50 and 51 and serves as a passage for the cigarettes and arranges them in position to reach a vertical conduit 67 through which the blanks 95 fall. Said conduit is provided at the lower end with a butt 68 which may be held in adjusted position by a screw 69. At the sides of this conduit are fixed by their upper ends small metal sheets or hoops 70 whose lower ends are free. On the outer faces of these small sheets bear the widened ends of horizontal stems 71 passing through openings 72 in the walls of the conduit 67 and terminated at its outer ends in bevel heads 73, 100 the helical springs 74 being coiled in the portions of these stems outside of the conduit. Heads 73 bear against cam 75 at the upper end of vertically movable rods 76. Said rods operate in sleeves 77 mounted 110 through openings on table 3 underneath which are coiled on the bars the tension springs 78. At lower ends of rods 76 are yokes 79 which have vertical slots 80 through which pass shafts 5 and 4 whereon are fixed 115 cams 30 and 35 which bear rollers 82 and operate said rods as will be understood.

The rear wall of conduit 67 has an extension at its upper end which is inclined and one which is a casing 83 which has 120 openings 84, said casing forming a vacuum chamber which is in communication with a tube 85 that leads to a suction pump or other similar device, not shown. Said tube has a cut off valve 86 whose stem 87 is 125 provided with a spring and terminates in a head actuated by the cam 30' mounted on shaft 4. At the sides of the conduit 67 are exteriorly articulated the rods 89 whose upper ends are exteriorly pivoted on 130

the upper part of the sides of a blank feeding deposit 90 having an inclined bottom opened at its front and rear part, being provided at its front part with clips 91 fixed 5 to its sides which serve to secure the blanks and prevent them from falling. The edge of the lower end of said blank feeder is raised up as indicated in 91' to constitute a further catch for the blanks. The blank 10 feeder or deposit 90 has an alternative movement from back to front by means of a mechanism that will be now described. On the rear wall of the cigarette recorder are fixed horizontal brackets 92 and between 15 them is rotatably mounted a horizontal shaft 93 on which are fixed the levers 94 articulated to links 95 which in turn are articulated to lugs 96 projecting from the lower face of the blank feeder bottom. On a projecting end of shaft 93 is fixed an arm 93' 20 articulated on the forked ends of a vertical bar 97 provided with tension spring 97' and actuated by cam 31' of the shaft 5.

The folder is formed by a fixed part and 25 a movable part. The fixed part comprises a bottom plate 98 arranged on table 3 and being of double T shape and provided with a removable cover 99 of the same shape, said parts being separated by the blocks 30 100 at the front end to which is fixed an inner rounded claw 101 constituting a guide for bending or folding the edges of the closed end of the wrapper by means of a screw 102 passing through corresponding 35 grooves in lid 99 and serves for approaching or separating from each other the blocks 100 and at its near ends by blocks 103 where there are fixed inner pieces 104 presenting a curved ascending surface for bending up 40 wardly the side edges of a blank by means of a screw 105 passing through slots 106 on lip 99 and which serves to approach or separate from each other said blocks. On the sides of the central branch of the cover 45 108 one of whose branches bear on the upper face of lid 99 and the other branch pends downwards, said plates being secured to the lid by means of screws 109 operating through 50 slots 110 which arrangement permits the approaching or separation of said plates according to the size of the wrapper, a part of them constituting the side wings 107 vertical at their rear portion and raised at 55 its fore end forming lugs 107' for bending downwards the upper side edges of the blanks.

On the folder is mounted the paster which 60 comprises two rollers 111 and 112 which rotate towards each other supporting frames 113'. Rollers 113 contact with roller 112 approach wings 107 which rub the paste they receive from rollers 112 and 113 to the inner face of the lower side edges of the 65 blank when they pass extended beneath said

wings 107. Rollers 111 and 112 and the pasting wheels 113 are moved by means of a vertical shaft 114 provided at its lower end with a bevel pinion 115 meshing at right angles with pinion 36 mounted on 70 shaft 4 and on its upper end has another bevel pinion 116 meshing with a bevel pinion 117 on the shaft of roller 112 which transmits motion to the other roller 111 and to the wheels 112 by means of gears 118, 119 75 on the shaft of roller 111 and another gear wheel 120 at its opposite end meshing with a gear wheel 121 on the shaft of the pasting wheels 112.

The movable part of the folder comprises 80 a tube of rectangular section formed by a piece 122 constituting the bottom and side walls and a lid 123 provided at its center with a low cut fixed by means of screws 124 to the side walls of the tube. At its front end the tube has a downwardly extending plate 125 slidable between vertical guides provided on a guiding plate 126 at the rear end of the machine supporting 90 frame. At the side of pieces 122 is pivoted at 127' a yoke-shaped plate 127 and from the cross portion 128 of the latter project rearward at its lower edge two horizontal lugs 129 and project forward at the middle 95 of its upper edge a lug 129' with the object that will be herein after explained and which plate 127' in the normal portion of the outlet tube rests on lid 99 of the fixed or stationary part of the folder. The side 100 folds at the open head of the wrapper are formed by two opposite fingers 130 arranged to slide in brackets 103 fixed on the opposite end of frame 2 and to move into and out of the part of the wrapper, said 105 fingers being provided with trunnions 131 which pass through horizontal slots 132 in said end of frame 2 and enter respectively 110 in the forks at the upper ends of two armed levers 132 and 143 pivoted on the fixed plate 126. Said lines have at the ends of their short arms small rollers 135 and the long arms of said levers are connected together by a horizontal spring 136 which is active 115 to approach them. The small rollers 135 on the short arms of the levers are actuated by the cams 31 and 37 mounted on shafts 4 and 5. The slidable plate 125 is caused to be moved between the guides provided in the fixed plate 126 by means of a connecting bar 137 articulated to a two armed lever 138 exteriorly pivoted to the rear end 120 of frame 2 and at the end of the shorter branch of which bears a small roller 139 actuated by cam 38 mounted on shaft 4 125 (Fig. 4). On the rear part of the supporting frame of the paster is a transverse rock shaft 140 which has fixed at one end at the exterior of the frame a plate 141, which is forced to be inclined downwards a helical 130 spring 142. On shaft 140 is fixed an arm

143 on which is mounted a small roller 144 arranged to come in contact with roller 111. Shaft 140 is caused to be rocked by an arm 141 with a spring 142 and a vertically movable rod 146 with a screw 148 for fitting the rod in position. In said bar is provided a collar 149 bearing at its end a small roller 150 and between the same and the collar is coiled a spring 151, the bar 146 being actuated by cam 32 mounted on shaft 5.

At continuation of the outlet tube there is a conduit provided with means for drying the wrapper when finished comprising open ended casing 152, lid 153 hinged on 154 and 15 which is fixed by means of a screw 155 passing through a low cut at the side of its free end. Said casing 152 is arranged in alignment with the outlet tube with a slight separation with the same as indicated in 156 (Fig. 7) and hinged at 157 at the bottom of the outlet tube. At the bottom of casing 152 there is a binding-post 157' to which are connected the wires 158 connected to an electric generator which is not shown.

25 The operation of the machine is as follows: The driving shaft 9 being put in operation by the fast pulley 11 rotates also the shafts 4 and 5 through the gears 6, 7 and 8 and the transmission members mounted on these shafts are accordingly moved. Thus, through bevel pinions 20 and 21 imparting motion to crank 17 and from this through connecting-rod 16 to lever 15 which through link 22 cause the block 23 to move along 35 guides 24 with a reciprocating alternative motion.

The case 39 of the magazine being filled with cigarettes and the case 90 of the blank feeder filled with wrapper blanks 159, the cigarettes fall in the space 43 and 44. When the block 23 comes near the magazine 39 the pushing plunger 25 enters into the central chamber 42 and the boards 26 and 27 enter into the spaces 43 and 44 and cause the cigarettes occupying these spaces to pass to the cases 50 and 51 of the compressor. When the boards 26 and 27 draw back new cigarettes fall in the spaces 43 and 44 this fall aiding the vibratory motion imparted to the frame 46 by lever 47 which motion shakes laterally the cigarettes in the case. When the cigarettes are in the parts 50 and 51 of the compressor, the cams 29 and 34 of shafts 4 and 5 actuate the levers 60 and 61 thus pushing the compressing plungers 58 and 59 inwardly in the casings 50 and 51 pushing the cigarettes 160 pressing them in the center above and below the horizontal partition thus forming two layers of cigarettes separated by this partition.

When the cigarettes are in this position the plunger 25 advances in another stroke and pushes the cigarettes by their end causing them to pass to the conduit 66 and at this time the cams 29 and 34 effect the back-

ward stroke of the plungers 58 and 59 to give way for the new cigarettes that are being pushed by the boards 26 and 27 in the same stroke of plunger 25.

During that revolution in the cam 35 which actuates the vertical lever connected to the blank feeder 90 inclines the same forward and causes the suction case 33 in which a vacuum has been created to catch a blank and when the blank feeder 90 returns to its initial position owing to the movement of the cam operating the same, the cam 30' actuating the valve 83, the cut-off, the vacuum and the blank 159 falls in the conduit 67. At the end of its fall, the sheets 70 actuated by the stems 71 operating the heads 75 at the ends of bars 76 actuated by cams 30 and 35' maintain the blank in a vertical position so that there may be projects at each side of conduit 66 portions of exactly the same size 85 so that on passing the two layers of compressed cigarettes through the conduit 67 pushed by plunger 25 cause the blank 159 to be folded at its middle portion as shown in Fig. 7 of the drawings, causing same to 90 enter in the folder and at the same time of entering between the bottom and cover thereof of the rounded claws 101 form the side folds of the closed ends of the wrapper as illustrated in Fig. 21. The package continues 95 advancing and the side lugs 107' and wings 107 fold the upper side edges of the blank downwards that were extending as illustrated in Fig. 23 at this moment when passing the lower side edges of the blank in extended position beneath the wheels 113 which 100 receive the gum or paste from the paster by contact with roller 112, they take the paste from said wheel; on reaching the lower side edges of the blank in front of the inner projections 104 of its ascending curved periphery they fold upward the lower side flanges of the blank as shown in Fig. 24, the same being pasted to the upper side edges when the package enters the outlet tube 122, at 105 which immediate moment, that is, when the package is wholly inside the tube having only out the end edges of the open head of the blank, the side fingers 130 operated by cams 31 and 37 are moved towards each other, the spring 136 approaches the upper arms of levers 133 and 134 connected to said fingers 130 which fold inwardly the side edges of the open end of the wrapper as illustrated in Fig. 25, the fingers 130 then immediately withdraw through the continued action of cams 31 and 37. In this position of the package the small movable roller 144 is in contact with roller 111 of the paster and lugs 129 of plate 127 bear against the cover or lid 99 of the folder. As soon as the fingers 130 draw back, the sliding plate 125 is raised between the guides of the stationary plate 126 and tube 122 is raised 110 carrying along the package with the end 120 115 125 130

edges of the wrapper blank 159 extended and also elevating the plate 127, the free end of which, being unsupported, will drop the plate 127 thus it will bend downwards the 5 upper end edge of the blank as shown in Fig. 26, which will be kept in that position while the vertical bar 137 is held upward by the action imparted by cam 38 to the small roller 139 and said roller 144 rubs paste to 10 the inner face of the end lower edge of blank 159, and when descending the sliding plate 125 the end lower edge of the blank 159 which has also passed above the lid 99 is caused to be pasted on the upper edge by 15 this same lid 99 as illustrated in Fig. 27, both edges being thus pasted and the wrapper is thus finished, and the wrapper in another stroke of the plunger is pushed out of tube 122 by the next following wrapper, and is 20 then introduced in the drying case 152 where it will be readily dried in a few moments, coming out finally therefrom by the pushing of the next following wrapper.

Although it has been illustrated a blank 25 feeder having motion with respect to a blank extracting device, it is obvious that in the reverse the blank extracting device could be provided with movement and the blank feeder kept without motion by means of a 30 simple variation of the constructions which does not affect the substantial idea of the invention.

Some other similar variations can be introduced without departing from the fundamental idea of the invention, and accordingly I do not limit myself to the construction described, but would have it understood that such changes may be made within the scope of the appended claims.

40 What I claim is:

1. In a wrapping machine, folding means including a bottom, a lid, laterally adjustable guides for folding downwardly the upper side edges of the blank or wrapper, adjustable rear and front guides pieces for

forming the side folds of the closed head of the blank and for folding up the lower side edges thereof, means to fold inwardly the side edges of the open head of the blank, a duct arranged at the discharge end of the folding device and mounted for movement into and out of line with the path of the wrapped article, means in said duct for folding down the upper portion of the open end of the blank and to hold the same in folded 50 position while the duct is out of line with said path, means for applying paste to the outer face of the lower edge of such end of the blank and means to complete the closing and pasting of the open end of the blank 55 when said duct returns into alignment with said path.

2. In a wrapping machine, folding means including a bottom, a lid, laterally adjustable guides for folding downwardly the upper side edges of the blank or wrapper, adjustable rear and front guides pieces for forming the side folds of the closed head of the blank and for folding up the lower side edges thereof, means to fold inwardly the side edges of the open head of the blank, a duct arranged at the discharge end of the folding device and mounted for movement into and out of line with the path of the wrapped article, means in said duct for folding down the upper portion of the open end of the blank and to hold the same in folded 70 position while the duct is out of line with said path and comprising an element pivotally mounted on said duct and movable 75 to open position by contact with said folding device when said duct is in line with said folding device, means for applying paste to the outer face of the lower edge of such end of the blank and means to complete the closing and pasting of the open end of the blank when said duct returns into alignment with said path.

35 In witness whereof I affix my signature.

HERNÁN C. BELLIDO.
